(57) **CLAIM**

The ornamental design for a dog cage, as shown and described.

DESCRIPTION

FIG. 1 is a front perspective view of a dog cage, showing the first embodiment of my new design;

FIG. 2 is a rear perspective view thereof;

FIG. 3 is a front perspective view in another angle of the dog cage;

FIG. 4 is a front elevation view thereof;

FIG. 5 is a rear elevation view thereof;

FIG. 6 is a left side elevation view thereof, the right side elevation view being a mirror image of FIG. 6;

FIG. 7 is a top plan view thereof;

FIG. 8 is a bottom plan view thereof;

FIG. 9 is an enlarged view of the portion outlined in FIG. 1;

FIG. 10 is an enlarged view of the portion outlined in FIG. 3;

FIG. 11 is a front perspective view of a dog cage, showing the second embodiment of my new design;

FIG. 12 is a rear perspective view thereof;

FIG. 13 is a front perspective view in another angle of the dog cage;

FIG. 14 is a front elevation view thereof;

FIG. 15 is a rear elevation view thereof;

FIG. 16 is a left side elevation view thereof, the right side elevation view being a mirror image of FIG. 16;

FIG. 17 is a top plan view thereof;

FIG. 18 is a bottom plan view thereof;

FIG. 19 is an enlarged view of the portion outlined in FIG. 11; and,

FIG. 20 is an enlarged view of the portion outlined in FIG. 13.

The dash-dot-dash broken line rectangles representing boundaries for the enlarged views shown in FIGS. 1, 3, 9, 10, 11, 13, 19, and 20 form no part of the claimed design.

1 Claim, 18 Drawing Sheets
